Corporation, Cleveland, Ohio, a corporation of
Delaware

Original application February 18, 1935, Serial No.
7,114. Divided and this application March 2,
1936, Serial No. 66,596

6 Claims. (Cl. 242—53)

This invention relates to apparatus for handling thread or the like and, more particularly, to the drive mechanism for such apparatus.

The present application is a division of prior application Serial No. 7,114, filed February 18, 1935, by Walter F. Knebusch and Alden H. Burkholder, in which is shown, described and broadly claimed a form of apparatus for the continuous processing of thread or the like, hereinafter referred to as "thread". On such apparatus, the thread, such as artificial silk thread manufactured by the viscose process, is continuously but temporarily stored on each of a plurality of rotatable thread-advancing devices, which preferably 10 take the form of thread-storage, thread-advancing reels, disposed in vertically stepped arrangement. Processing treatment is applied to the thread on each of said reels, after which the thread is collected by suitable apparatus. The 15 mechanism for driving the apparatus of said prior application, which mechanism is not specifically claimed in said application, constitutes the subject matter of the present application.

In the accompanying drawings, forming a part 20 hereof, Figure 1 is an end elevation of a complete thread processing machine of the kind described in said prior application, the means for applying processing medium to the thread on the reels being omitted and other parts being broken away for 25 the sake of clearness. Figure 2 is an end elevation, corresponding to Figure 1 but on a larger scale, of a portion of the machine with parts broken away more clearly to show the drive mechanism and reels driven thereby. Figure 3 30 is an elevation on the same scale as Figure 2 of one operating face of the machine, corresponding to the operating face on the right of Figure 1, parts being broken away more clearly to show the drive mechanism. Figure 4 is a detail sectional elevation on a larger scale on approximately line 4—4, Figures 3 and 5, through one of the thread-storage, thread-advancing reels and its adjacent driving mechanism. Figure 5 is a detail plan, on a slightly smaller scale than Figure 4, illustrating several of the reels and associated apparatus shown in Figure 4, the cover of the gear housing being omitted. Figure 6 is an end elevation of the reel of Figure 4 on the same scale and from the left end thereof. In the drawings, like reference numerals refer to like parts throughout.

While the apparatus described is capable of use in or in connection with the processing of any thread, for convenience it will be illustrated hereinafter as applied to the manufacture by a con-

tinuous process of multiple filament viscose artificial silk thread.

In the apparatus shown in Figure 1, the thread is formed by extrusion of the viscose into the coagulating bath 2, the thread being led to and progressed along a thread-storage, thread-advancing reel of cantilever form, designated 5, from which it passes to any suitable number of other like reels 5a to 5i upon which are performed any desired processing steps. The thread is led from the last reel 5i through a suitable guide to a collecting device such as cap-twister 7. The production of each multiple filament thread requires a complete series of such thread-storage, thread-advancing reels in numbers sufficient to enable 10 the desired processing steps to be performed on the thread. However, as is usual in this art, a given machine may be built to provide for the simultaneous production of a multiplicity of such threads; so that each machine may include a plurality of such series arranged in such manner as to enable the parts thereof to be conveniently accessible for inspection, manipulation, or control, as well as to enable the plurality of such series to be driven from the same power source. 25

In the instant machine, the reels are shown as arranged in a plurality of descending series, on each of which the thread is subjected to the desired processing treatments. Since the reels shown are of cantilever form; i. e., supported 30 and driven from one end only, and since the thread is, by the action of the reels, advanced axially thereof, they may be positioned, as shown, in stepped arrangement with the receiving end of each reel immediately below the discharge end of 35 the next preceding reel. The unsupported ends of the reels, constituting the discharge ends, are presented to the operator. This arrangement provides advantages in construction of the processing apparatus as well as advantages in permitting 40 access to the reels for manipulation of the thread, inspection, repairs, etc.

Furthermore, it has been found desirable to position the reels in adjacent series, so that corresponding devices will be in corresponding positions, the reels thus being disposed in a plurality of horizontal series extending longitudinally of the machine. This disposition of the reels in a plurality of longitudinal series results in simplification of the construction of the processing medium supply and removal systems as well as advantages in driving the reels, as will be herein-after explained more in detail in connection with the drive mechanism provided by the present invention. Therefore it can be seen that the reels 50 55

in one operating face of the machine may be disposed, with their axes substantially horizontal, in a plurality of series in a bank inclined as a whole from the vertical. Furthermore, the machine, may, as shown in Figure 1, be double-sided, having an inclined bank on each side of the machine.

The machine shown in Figures 1 to 3, inclusive, comprises a suitable frame including lower and upper platforms 8, 9, carried by crossbeams 11 supported from corner posts 12, the platforms 8, 9 being connected by diagonal uprights 13, 14. The drive mechanism for the reels in the illustrated apparatus has as a source of power a drive motor 18 which is mounted at one end of the machine, as in Figure 3, the shaft of which motor actuates a suitable speed reducing device 19 operating a cross shaft 20 provided at its opposite ends with bevel gears 21 driving bevel gears 22 on diagonal shafts 23, of which one may be provided on the left side and one on the right side of the machine, as shown in Figure 1. Diagonal shafts 23, which for convenience may be termed the main drive shafts, are provided at various levels with take-off drives for the reels 5a to 5i, inclusive, and the driving connections to the several reels may, if desired, include any suitable form of change speed mechanism. For convenience the shafts 23 and the drive connections therefrom to the several reels may be located at one end of the machine as shown in Figures 2 and 3.

As the drive connection from either main drive shaft 23 to each of its corresponding reels 5a to 5i is the same, description of one will suffice for all. Thus, for the drive to each of the reels 5a to 5i, main drive shaft 23 is provided with a spiral gear 60 driving a spiral gear 61 (Figure 2) on a short horizontal shaft 62 parallel to the front of the machine, as shown in Figure 3. Shaft 62 is provided with a gear 63 which drives a gear 64 on a shaft 41 mounted on a slotted bracket 66, pivoted to turn about a shaft 67 and held in any adjusted position by a cap-screw 44 passing into the frame of the machine through a curved slot in said bracket. Shaft 41 also carries a gear 65, adapted to rotate with gear 64, and meshing with a gear 68 mounted for rotation with shaft 67. Shaft 67 which may for convenience be termed the intermediate drive shaft extends horizontally and longitudinally along the operating face of the machine and is provided with suitable driving means for the corresponding horizontal or longitudinal series of reels disposed along the shaft.

The means for driving each reel from the intermediate drive shaft 67 is shown to better advantage in Figures 4 and 5. As shown, the driving means may be enclosed in a longitudinally extending housing 76, which may also serve as a lubricant reservoir for the parts therein, and which may be provided with a removable cover 77, with a series of internal bearing bosses 78 on one of its walls and opposite to them, a series of external bearing bosses 79 on the opposite wall. Cover 77 is provided on its inner surface with a depending portion 77a having inclined sides and faces adapted to direct downwardly upon the gear 71 any lubricant splashed in the housing. Intermediate drive shaft 67 extends longitudinally of the housing, its outwardly projecting ends being connected by couplings 75 to like ends of neighboring shaft sections. The shafts 72 for the reels are journaled in the bearing bosses before referred to, and extend across the housing 76 and shaft 67. In the illustrated apparatus, each shaft 72 projects from one of the longitudi-

nal walls of the housing 76 and drives a reel from its projecting end.

In the apparatus shown, each reel in the horizontal series is mounted on one face of the housing 76 and is driven from intermediate drive shaft 67 by a spiral gear 70 mounted thereon and engaging a spiral gear 71 rotatably mounted on reel drive shaft 72. Spiral gear 71 is provided with a clutch member 73a cooperating with a clutch member 73b splined to the shaft 72 and having a grooved collar 52 in the groove of which is disposed the fork 53 of a rod 54 connected to one arm of a controlling bell crank lever 74. Figure 4 shows the clutch members 73a, 73b in engagement, so that shaft 72 may be rotated. By turning the bell crank lever 74 clockwise in Figure 4, the clutch members 73a, 73b may be disengaged to stop the rotation of the corresponding reel. Each reel, may, as shown, be provided with its individual clutch, and the levers 74 for all of the reels may be individually operated. However, for convenience, the levers 74 for reels 5a to 5i of a vertical series may be connected by a bar 135 having an operating handle 136 at a convenient point so that all of the reels in one vertical series may be started and stopped simultaneously.

For the foregoing and other reasons, the drive mechanism herein described provides in operation an unusually high degree of flexibility. For instance, in addition to the above mentioned provision for stopping all the reels in a given vertical series, any horizontal series of reels may be disconnected from the primary drive shaft by loosening cap-screw 44 and swinging bracket 66 to the right in Figure 2, thus disengaging the driving gearing. By substituting a gear of a different size for any one or more of the gears 63, 64, 65, 68, any desired speed ratio may be established between any of the shafts 23 and shaft 67. The speeds of the reels in a vertical processing series with respect to the main drive shaft 23 and with respect to each other may thus be varied as desired. This is particularly advantageous when it is desired to provide different peripheral speeds between an earlier reel and a later reel for the purpose, for example, of stretching of the thread.

The rotatable thread-advancing devices of the instant apparatus may take the form of a thread-storage, thread-advancing reel of the type shown in Figures 4 and 6, which is of the same general form and operates in the same manner as the reel shown and described in British Patent No. 413,414. The reel shown is, however, of cantilever form in the sense that the supports for said reel are connected to it at one end only, leaving the thread-supporting bars unobstructed at the other end of the reel. Therefore by rotating the reel in the proper direction to cause the turns of thread to travel from its driven end to its unsupported end, the task of transferring the thread from reel to reel is materially simplified due to the absence of a shaft extension and consequent ease of manipulation of the thread by the operator.

The typical form of reel shown in these figures includes two rigid, generally cylindrical members respectively designated 80 and 81. Member 80 may be termed the concentric member because it is concentric with, fixed to, and rotates with the reel drive shaft 72. Member 80 includes a body portion of generally cylindrical form with its periphery slotted to form a series of alternating bars 82 and recesses 83, the body portion be-

ing mounted upon a sleeve 84 keyed to the shaft 72 and held in place thereon by a nut 85 threaded upon the end of said shaft. The other member 81 of the reel may be called the eccentric member, because while it is generally of cylindrical form it is mounted with its axis laterally offset slightly from and disposed inclined to the axis of the shaft 72. The member 81 as shown comprises a head formed of inner and outer rings 87, 88, the former of which has peripheral slots to receive the bars 89. The bars are clamped between the rings 87, 88, which are held together by screws 81a. Inner ring 87 is mounted on a sleeve 90 journalled to rotate upon a supporting member 91 which surrounds shaft 72 and is spaced therefrom. Means are provided for supporting member 91 with its axis slightly offset laterally from and inclined with relation to the axis of shaft 72.

Rotation of the drive shaft 72 causes concentric member 80 fixed thereto to rotate, whereupon contact of bar members 82 of concentric member 80 with bar members 89 of eccentric member 81 causes said eccentric member to rotate. The thread is thus caused to wind on the reel, the degree of the inclined relation determining the lead or pitch of the turns of thread wound in generally helical form upon the reel and progressively advanced along it. With a reel of this general type any desired length of thread within reasonable limits may thus be temporarily continuously stored in a plurality of advancing turns.

Reels of the form shown in Figures 4 and 6 may be employed for the of the reels 5 to 5h inclusive, Figure 1, since it may be desirable to apply wet processing treatments to the thread while stored on certain of these reels. However, it may be desired to dry the thread on the reel 5i before it is collected, as by cap-twister 7, in which case the reel 5i, while of the same general type and operating in the same general manner as the others, may be adapted to supply drying medium to the thread stored on the reel from the interior of the reel, as described in detail in said prior application Serial No. 7,114. As hereinafter explained, means are provided for subjecting the thread on one or more of the reels 5a to 5h to suitable wet processing operations; to wit, means disposed above each of said reels for supplying to said reel a spray or series of small streams of processing liquid, troughs for collecting said processing liquid as it drains from the reel, and apparatus for recirculating the liquid or conducting it to the sewer.

By reference to Figures 2, 3 and 5, it can be seen that each trough 108 may be suitably formed to collect the liquid and prevent splashing thereof, and may be provided with a re-entrant portion 118 below each reel to allow the transfer of the thread from reel to reel. Because of the arrangement of the reels in the machine in a plurality of horizontal or longitudinally extending series it is possible to have each trough serve several corresponding reels in adjacent processing series. Likewise the liquid distributing system may also serve corresponding reels in adjacent series and may comprise a suitable reagent distributor 115 positioned above each reel and supplied from a common supply conduit 113 extending longitudinally of the machine. Each trough 108 may communicate either with a sewer, as in the case of wash water or other liquid which is to be discarded, or, as in the case of liquids which it is desired to re-use, with suitable re-

circulating and make-up systems, from which it is passed to the corresponding supply conduit.

Referring now to Figures 2 and 3 for other details of the apparatus shown, the collecting device comprises a cap-twister 7 of substantially standard form. Each vertical series of reels disposed in processing sequence is provided with one of said twisters, a plurality thereof being driven by the same power source. As illustrated, the machine is provided with a long drum 119 connected by belts 120 to the whirs of the cap-twisters, belts 120 having belt tighteners 120a. Drum 119 is driven by a belt 121 actuated from the drive shaft of the speed reducing mechanism 19 which is driven by motor 18.

For reciprocating the cap-twisters a speed reducing device 122 is provided driven by a belt 123 from a pulley on shaft 20. The shaft 124 of such speed reducing device is provided with a cam 125 actuating a lever 126 pivoted on the frame at the point 127 and connected by tension members 128 to cap-twister lifting rods 129, slidably vertically in frame guides 130 and connected by bars 131 which carry the whirs of the cap-twisters, the vertically moving parts being partly counterbalanced by weights 132. The function of drums 119 and cams 125 is to rapidly rotate and vertically reciprocate the spindles of the several cap-twisters, so that the thread is twisted and wound in the usual form upon the spool or bobbin.

It is apparent from the above description and from the drawings that in the apparatus illustrated as embodying the invention the parts handling the threads in both banks are driven in timed relation, which makes for uniformity of all threads produced on the machine. Moreover, it is apparent that in the illustrated apparatus the driving mechanism is of such a nature that the interior of the apparatus is substantially unobstructed, permitting ready access by the operators to all parts of the apparatus even though it may be of substantial size. This is extremely advantageous for adjustment, replacement and other maintenance purposes.

Various changes and modifications may be made in the driving mechanism herein described without departing from the spirit of the invention. The invention is not restricted to the driving of thread-storage, thread-advancing devices of the form shown, but may be applied to the driving of various other devices. In the appended claims, the term "thread" includes, besides thread per se, materials other than thread capable of being handled by apparatus of the kind shown and described.

It is intended that the patent shall cover, by suitable expression in the appended claims, whatever features of patentable novelty reside in the invention.

What is claimed is:

1. Apparatus for handling thread comprising two oppositely inclined banks of parallel, substantially horizontal drive shafts, the drive shafts of each of said banks extending in a direction generally opposite to that of the drive shafts of the other bank; thread-storage, thread-advancing devices associated with the drive shafts of each of said banks, said thread-storage, thread-advancing devices being arranged in a plurality of series each of which handles a single thread; a plurality of intermediate drive shafts each of which is disposed transversely of and adapted to operate a plurality of said drive shafts; a plurality of main drive shafts, at least one for each of said banks, disposed transversely of and

- adapted to operate said intermediate drive shafts; and, disposed between said banks, common drive means for said main drive shafts so arranged that the space between said banks is largely un-
5 obstructed.
2. Apparatus for handling thread comprising two upwardly extending banks of parallel drive shafts, the drive shafts of each of said banks extending in a direction generally opposite to that
10 of the drive shafts of the other bank; thread-storage, thread-advancing devices associated with the drive shafts of each of said banks, said thread-storage, thread-advancing devices being arranged in a plurality of series each of which
15 handles a single thread; a plurality of intermediate drive shafts each of which is disposed transversely of and adapted to operate a plurality of said drive shafts; a plurality of main drive shafts, at least one for each of said banks, disposed
20 transversely of and adapted to operate said intermediate drive shafts; and, disposed between said banks, common drive means for said main drive shafts so arranged that the space between said banks is largely unobstructed.
- 25 3. Apparatus for handling thread comprising two laterally extending banks of parallel drive shafts, the drive shafts of each of said banks extending obliquely to the plane of the bank as a whole in a direction generally opposite to that of
30 the drive shafts of the other bank; thread-storage, thread-advancing devices associated with the drive shafts of each of said banks, said thread-storage, thread-advancing devices being arranged in a plurality of series each of which
35 handles a single thread; a plurality of intermediate drive shafts each of which is disposed transversely of and adapted to operate a plurality of said drive shafts; a plurality of main drive shafts, at least one for each of said banks,
40 disposed transversely of and adapted to operate the intermediate drive shafts of such bank; and, disposed between said banks, common drive means for said main drive shafts so arranged that the space between said banks is largely un-
45 obstructed.
4. Apparatus for handling thread comprising two upwardly extending banks of parallel drive shafts, the drive shafts of each of said banks extending in a direction generally opposite to that of the drive shafts of the other bank; thread-
50 storage, thread-advancing devices driven by the drive shafts of each of said banks, said thread-storage, thread-advancing devices being arranged in a plurality of series each of which handles a single thread; a plurality of intermediate drive shafts each of which is disposed transversely of and operatively
55 connected to a plurality of said drive shafts, each of said intermediate drive shafts being substantially parallel to the plane of the bank with which it is associated; a plurality of main drive shafts, at least one for each bank, disposed transversely of and operatively connected to said intermediate drive shafts; and common drive means for said intermediate drive shafts, the arrangement of said common drive means, drive shafts, intermediate drive shafts and main drive shafts providing a substantially unobstructed space between said banks.

the bank with which it is associated; a plurality of main drive shafts, at least one for each of said banks, disposed transversely of and operatively connected to said intermediate drive shafts; and common drive means for said main drive shafts, 5 the arrangement of said common drive means, drive shafts, intermediate drive shafts and main drive shafts providing a substantially unobstructed space between said banks.

5. Apparatus for handling thread comprising 10 two oppositely inclined banks of parallel, substantially horizontal drive shafts, the drive shafts of each of said banks extending in a direction generally opposite to that of the drive shafts of the other bank; thread-storage, thread-advanc- 15 ing devices driven by the drive shafts of each of said banks, said thread-storage, thread-advanc- ing devices being arranged in a plurality of series each of which handles a single thread; a plurality of intermediate drive shafts each of which is disposed transversely of and operatively connected to a plurality of said drive shafts, each of said intermediate drive shafts being substantially parallel to the plane of said bank with which it is associated; a plurality of main drive shafts, at 20 least one for each of said banks, disposed transversely of and operatively connected to said intermediate drive shafts; and common drive means for said main drive shafts, the arrangement of said common drive means, drive shafts, intermediate drive shafts and main drive shafts providing a substantially unobstructed space be- 25 tween said banks.

6. Apparatus for handling thread comprising 30 two laterally extending banks of parallel drive shafts, the drive shafts of each of said banks extending obliquely to the plane of said bank as a whole in a direction generally opposite to that of the drive shafts of the other bank; thread- 35 storage, thread-advancing devices driven by said drive shafts, said thread-storage, thread-advanc- 40 ing devices being arranged in a plurality of series each of which handles a single thread; a plurality of intermediate drive shafts each of which is disposed transversely of and operatively 45 connected to a plurality of said drive shafts, each of said intermediate drive shafts being substantially parallel to the plane of the bank with which it is associated; a plurality of main drive shafts, at least one for each bank, disposed transversely of and operatively connected to said intermediate drive shafts; and common drive means for said intermediate drive shafts, the arrangement of said common drive means, drive shafts, intermediate drive shafts and main drive shafts providing a substantially unobstructed space between 50 said banks.

WALTER F. KNEBUSCH.
